UNITED STATES PATENT OFFICE

IRENEÉ P. PEDRICK, OF PHILADELPHIA, PENNSYLVANIA, ASSIGNOR TO WILLIAM SELLERS & COMPANY, INCORPORATED, OF PHILADELPHIA, PENNSYLVANIA, A CORPORATION OF PENNSYLVANIA

INJECTOR

Application filed October 28, 1927. Serial No. 229,316.

My invention relates to an improvement in injectors and may be adapted to injectors of various types including duplex injectors.

More particularly, my invention relates to the provision of an injector having a feed line check and overflow valve so arranged that the overflow valve will be automatically controlled through the medium of the line check. More particularly, the injector according to my invention is so arranged that when sufficient velocity of the feed water to overcome boiler pressure is developed in the forcing tubes the overflow valve will be closed with the opening of the line check. Conversely, if the velocity of the feed water for any reason falls below that necessary to overcome boiler pressure and the line check closes, the overflow valve will be permitted to open enabling the requisite velocity of the feed water to be again attained. Thus, the injector according to my invention operates to start and restart automatically on the turning on of the high pressure steam supply, or, in the case of a duplex injector, of the high and low pressure steam supplies.

Having now indicated, in a general way, the nature and purpose of my invention, I will proceed to a detailed description of a preferred embodiment thereof with reference to the accompanying drawings in which:—

Fig. 1 is a partial sectional view of an injector embodying my invention.

Fig. 2 is a fragmentary view, partly in section, of an injector similar to that shown in Fig. 1, modified in certain structural details.

Fig. 3 is a sectional view of a line check valve.

Fig. 4 is a sectional view of an overflow valve.

Referring more particularly to Fig. 1, *a* indicates a casing in which is positioned a set of forcing tubes *b*. The casing is provided with a steam inlet *c* leading to a chamber *d* with which communicates a steam nozzle *d'*, which discharges into the forcing tubes. An inlet *e* is provided for the admission to the forcing tubes of feed

water, or of water and steam from a set of mixing tubes if the injector be a duplex. The forcing tubes are provided with annular opening *f*, opening into an overflow chamber *g* in the casing and provided with an outlet *h*. The forcing tubes discharge into a delivery chamber *i* provided with a discharge outlet *j* adapted to be connected with a feed water line *j'* to a boiler, communication between the outlet *j* and the line *j'* being controlled by a line check valve *k*.

The outlet *h* from the overflow chamber is adapted to be connected to a waste line *h'* and communication between the outlet and waste line is controlled by a valve *l*. The valve *l* is yieldingly held on its seat by means of a coil spring *m*, which bears on top of the valve and against a piston *n* loosely fitted in a cylinder *o* in a plug *o'* threaded into the casing *a*, bearing against a ring *p*, provided with an internal flange *p'*, positioned above valve *l*.

The plug *o'* is provided with a bore *q* adapted to afford communication between the cylinder *o* and the delivery chamber *i*. Within the bore *q* extends a winged extension *r* from a valve *r'*, which controls communication through the bore. The stem *s* of valve *r'* extends through a gland *t* into a cylinder *u* formed in the underside of valve *k*, and is provided with a head *v*.

In the operation of the device embodying my invention as illustrated in Fig. 1, it being assumed that the injector is not in operation, the line check valve *k* will be closed under the influence of boiler pressure and the overflow valve *l* will be free to open. If now the injector is put in operation high pressure steam will pass up through nozzle *d'* into the forcing tubes *b* and water will enter the forcing tubes through inlet *e*. Initially the velocity in the forcing tubes will be insufficient to overcome boiler pressure, hence the line check valve *k* will remain closed and overflow from the forcing tubes will occur through openings *f* into chamber *g* and from thence through valve *l*, which will be lifted from its seat by the pressure in chamber *g*.

When the velocity through the forcing

tubes is sufficient to overcome the boiler pressure the line check valve *k* opens under the influence of pressure in the delivery chamber *i*. When the valve *k* has opened 5 slightly, the inner end of gland *t* engages the head *v* on stem *s* of valve *r'* and raises valve *r'* from its seat permitting part of the water of delivery from chamber *i* to pass down through bore *r* and act on piston *n* in 10 cylinder *o*. Piston *n* is forced downwardly under pressure and effects the closing of the overflow valve *l* through compression of spring *m*. The piston *n* is stopped by engagement with flange *p'* on ring *p* so that 15 the spring *m* is not compressed more than requisite to close valve *l* against overflow pressure, in order that should the velocity in tubes *b* decrease and the line check close, the valve *l* will reopen under the pressure of 20 the resultant overflow, without delay. When the valve *r'* is closed water in the cylinder *o* will by-pass piston *n* as the piston is raised on the opening of valve *l*.

Thus it will be noted that on the starting 25 of the injector embodying my invention when sufficient velocity has been developed in the forcing tubes to overcome boiler pressure and open the line check, the overflow valve will be automatically closed. Further, 30 it will be observed that if the feed is interrupted for any reason and the line check closes, the overflow may reopen and the feed will be automatically restarted.

Referring now to Fig. 2, in which a modification of my invention is shown, an injector is indicated at 2, the discharge outlet from the forcing tubes being indicated at 3 and the overflow outlet from the forcing tubes being indicated at 4. An overflow 40 valve 5 controls the overflow outlet and is held on its seat by means of a spring 6, confined between a pair of telescoping cups 7 bearing respectively on the valve 5 and beneath a piston 8. A passage 9 is provided in 45 the bottom of the lower cup 7 for the escape of air or steam from between the cups. Above the piston 8 is a chamber 10 in communication, through an outlet 11 and a pipe 12, with a duct 13, the upper end of which 50 extends into the discharge outlet 3. The discharge outlet 3 is connected with a boiler feed line 14 and is controlled by a line check valve 15. The valve 15 is provided on its top with an extension forming a chamber 16 55 closed at the bottom by a gland 17 through which extends the stem 18 of a valve 19 adapted to seat on the upper end of duct 13 and provided with a winged extension, or guide 20 extending into duct 13. The stem 60 18 is provided at its upper end, within the chamber 16, with a head 21.

As will be appreciated, the device shown in Fig. 2 operates in the same manner as that shown in Fig. 1, in that when the line 65 check valve 15 is closed, the overflow valve

5 will open freely, while when the line check is opened the valve 19 will be lifted off of its seat on the end of duct 13 through engagement of gland 17 with head 21 on stem 18, and pressure from the discharge outlet 3 will pass through duct 13 and pipe 12 and into chamber 10, where it will act on piston 8 and effect the closure of overflow valve 5, through compression of its spring.

Referring now to Figures 3 and 4, in which are shown an overflow valve and line check valve of modified construction, in Fig. 3, the discharge outlet of an injector is indicated at 30 and a boiler feed line at 31. The discharge is controlled by a line check valve 32 yieldingly held on its seat by a spring 33. The valve 32 is formed with a central boss 34 through which extends a stem depending from a plug 35 and provided with an axial passage 36 open at one end and in communication with lateral passages 37 adjacent its other end. The open end of passage 36 is connected through a suitable pipe with the cylinder 40 of the overflow valve shown in Fig. 4. In Fig. 4 an overflow outlet is indicated at 41 and is controlled by a valve 42 yieldingly held on its seat by a spring 43 confined between telescoping cups 44 with a cylindrical guide 45 on the valve 42 and provided with ports 46. The spring 43 bearing on the valve 42 and on a piston 47 within the cylinder 40 with which the passage 36 in the boss 34 is connected as has been indicated, the structure being similar to that described in connection with Fig. 2.

The operation of the line check valve and overflow valve of the construction shown in Figures 3 and 4 is similar to that described in connection with the devices of Figures 1 and 2, it being noted that when the line check valve 32 opens the lower end of boss 34 is raised above the lateral passages 37 permitting the passage of steam from the discharge 30 into the passage 36 and hence through suitable connections to the cylinder 40.

Having now fully described my invention, what I claim and desire to protect by Letters Patent is:—

1. In an injector, in combination, a delivery chamber, a line check valve, an overflow valve, a piston operatively connected to said overflow valve, a conduit affording communication between said delivery chamber and said piston, and means controlled by said line check valve for controlling the passage of fluid pressure from said delivery chamber to said piston through said conduit.

2. In an injector, in combination, a delivery chamber, a line check valve, an overflow valve, a piston, a spring confined between the overflow valve and the piston and adapted to yieldingly hold said overflow

- valve on its seat, a conduit affording communication between the delivery chamber and the piston, a valve controlling the passage of fluid pressure through said conduit and means affording an operative connection between said valve and said line check valve, whereby when said line check valve is opened fluid pressure will act on said piston and effect the closing of said overflow valve.
5. In an injector, an overflow valve, a feed line check valve, and means rendered operative by opening of the check valve when the delivery pressure exceeds boiler pressure to close the overflow valve.
10. In an injector, an overflow valve, a feed line check valve, and means rendered operative by opening compression of its spring and when said line check valve is closed fluid pressure will be shut off from said piston and said overflow will be free to open.
15. In an injector, an overflow valve, a feed line check valve, and means rendered operative by opening of the check valve when the delivery pressure exceeds boiler pressure to close the overflow valve.
20. In an injector, an overflow valve, a feed line check valve, and means rendered operative by opening of the check valve when the delivery pressure exceeds boiler pressure to maintain closed the overflow valve.
25. In an injector, an overflow valve, a feed line check valve, and means rendered operative by opening of the check valve when the delivery pressure exceeds boiler pressure to close the overflow valve, said check valve having an initial opening movement prior to
30. actuation of the means for closing the overflow valve.
35. In an injector, a delivery chamber, an overflow valve, a feed line check valve, and means actuated by fluid pressure in the delivery chamber and rendered operative by opening of the check valve to close the overflow valve.
40. In an injector, a delivery chamber, an overflow valve, a feed line check valve, and means actuated by fluid pressure in the delivery chamber and rendered operative by opening of the check valve to maintain closed the overflow valve.
45. In an injector, an overflow valve, a feed line check valve, means rendered operative by opening of the check valve to apply a closing force to close the overflow valve, and means limiting the closing force applied to the overflow valve.
50. In an injector, an overflow valve, a feed line check valve, means rendered operative by opening of the check valve to apply a closing force to maintain closed the overflow valve, and means limiting the closing force applied to the overflow valve.
55. In an injector, an overflow valve, a feed line check valve, fluid pressure operated means for closing the overflow valve, and means rendered operative by opening of the check valve to effect operation of said means by pressure of delivered fluid to close the overflow valve.
60. In an injector, an overflow valve, a feed line check valve, fluid pressure operated means for maintaining closed the overflow
- valve, and means rendered operative by opening of the check valve to effect operation of said means by pressure of delivered fluid to maintain closed the overflow valve.
- In testimony of which invention, I have hereunto set my hand, at Philadelphia, Pennsylvania, on this 20th day of October, 1927.
